Specification of Letters Patent. Patented Aug. 1, 1922.

Application filed December 13, 1920. Serial No. 430,568.

To all whom it may concern:

Be it known that I, JOSEPH B. HOWE, a citizen of the United States, and resident of Worcester, in the county of Worcester and 5 State of Massachusetts, have invented new and useful Improvements in Clutches, of which the following is a specification.

This invention relates to carding feeders and more particularly to a clutch mechanism for use in such machines whereby to control the operation of the "spike apron" and associated parts. A machine of the 10 general class to which this invention may be applied is illustrated in the patent to 15 Bramwell 216,373, June 10, 1879, the present invention relating to specific improvements in a clutch mechanism such as disclosed in the patent to Howe, 998,003, July 18, 1911.

The principal object of this invention is 20 to so improve a clutch of the above type as to render its operation certain at all times and to make it of practical utility under all usual conditions of employment.

In the accompanying drawings which 25 illustrate one embodiment of the invention;—

Figure 1 is a fragmentary elevational view 30 of the upper right hand side of the machine showing the clutch of this invention applied thereto;

Figure 2 is a side elevation of the clutch mechanism with the drive pulley removed but with a fragment thereof shown in section;

Figure 3 is a sectional view taken on the 35 line A—B of Figure 2, but showing the complete drive pulley in position on the shaft;

Figure 4 is a fragmentary elevation similar to Fig. 2, but showing the parts in 40 another position; and

Figure 5 is a fragmentary sectional detail on the line C—D of Fig. 2.

The frame of the carding feeder machine is indicated at 1, such frame having suitable 45 supporting and driving means for an endless carrier 2 provided with pins or spikes 3 whereby to elevate fiber from a suitable bin. This endless carrier is known in the art as a spike apron, and cooperating with the 50 down going side of such apron is an oscil-

lating doffing device mounted upon a shaft 4 and driven in any suitable manner. Cooperating also with the up going side of the spike apron is an oscillating comb carried by the arm indicated at 4^a and actuated in any 55 suitable manner.

Extending transversely across the machine frame near its upper part is a drive shaft 5 by means of which the spike apron, and if desired, the shaft 4 may be driven. The shaft 60 5 has loosely mounted thereon at the right hand side of the frame a pulley wheel 6. The pulley wheel 6 may be driven by means of belt, not shown, from any suitable source of power. 65

A scale pan 7 is arranged in position to receive the fiber doffed from the down going side of the spike apron, such pan being carried by a scale beam 8 fulcrumed at 8^a. The tipping of the scale pan 7 through suitable 70 connections as indicated at 9 serves to actuate a trip device 10. This trip device, in normal position, is operative to support the weighted end 13 of a dog 12 pivoted at 12^a upon a suitable bracket carried by the frame. The dog 75 12 has a tooth 11 engageable with teeth or lugs 14, carried by a clutch disengaging wheel 42, hereinafter referred to in detail.

For returning the dog 12 to normal position, a connecting rod 15 may have its upper 80 end pivotally secured thereto, the lower end of such connecting rod passing freely through an opening in a boss 15^a carried by a lever arm 16, such rod having a fixed stop member 15^b at its lower extremity. The 85 lever 16 is pivoted at 16^a and has a lower arm 19 and a lateral arm 22. Loosely engaging a pin carried at the outer extremity of the arm 22 is a loop 23^a at the lower end of a rod 23 secured to a member 23^b carried by 90 the scale pan.

The arm 22 with its connections just described serves on its downward movement to open the scale pan for dumping, and on its upward movement to restore the scale pan 95 and beam to normal position. The lever 16 is provided with a cam surface 21 engageable by a cam roll 20 carried by a rotating gear wheel 19^a, and the arm 19 of the lever 16 has a cam surface 18 for engagement by a 100

cam roll 17 moving with the wheel 19. The cam roll 20 thus serves to swing the arm 22 downwardly, while the roll 17 swings said arm upwardly and at the same time swings the arm 16 downwardly whereby to reset the dog 12 by means of the connecting rod 15 as above described.

Referring now to Figs. 2 to 5 inclusive, it will be noted that the pulley 6 is provided with a hub 6^a which is freely turnable on the shaft 5. Such hub at its inner end is reduced in diameter as at 34 and its reduced portion is received within the forward end of a sleeve 32 keyed upon the shaft. The pulley 6 may be retained on the shaft by means of a collar 37, or in other suitable manner. The inner side of the drive pulley 6 is provided with a flange 30 having upon its inner face a plurality of drive lugs 31. In usual practice three such lugs are found to be sufficient. Fixed upon the rear end of the collar 32 is a disk member 38 having a smooth peripheral surface 39. Forward of said disk 38 is a frame member 41 loose on the collar 32, and at 42 is a clutch disengaging wheel also loose on the collar 32.

In front of the wheel 42, the sleeve 32 is provided with a collar 40 which may be fixed thereto or integral therewith. Such collar bears against the forward surface of the wheel 42 and serves to maintain the latter in proper position on the sleeve.

The wheel 42 is provided with a forwardly directed flange 44 which encloses the collar 40, and upon its peripheral surface the wheel 42 is provided with the teeth 14 above referred to. Such teeth may be of any desired number, it being found in practice that thirty such teeth give desirable results.

45 is a sector fast to the sleeve 32, and if desired integral with the collar 40, said sector having pivoted thereupon, at the point 46, a dog member 47. The dog member 47 has a lug 48 engageable by any one of the lugs 31 of the drive pulley 6, whereby to rotate the shaft 5.

49 is an actuator having a toe 49^a which normally projects outwardly between end walls 50, 51 of the flange 44 of the wheel 42, such walls defining an opening 52 through the flange. The actuator 49 is pivoted upon a lug 53 projecting rearwardly from the sector 45. The actuator is provided with a forwardly extending pin 56 which projects through an arcuate slot 54 in the sector 45, of which slot the point 46 is the center of curvature. The pin 56 also projects loosely through an elongated slot 55 in the dog 47, said slot being substantially radial as respects the axis about which said dog turns.

The dog 47 is continued to the opposite side of the pivot point 46 to provide a tail 57 with which engages one end of a spring 58 which is coiled under tension about the forward end of the sleeve 32 (see Fig. 3).

The other end 59 of the spring 58 is secured in a lug 60, projecting forwardly from the face of the wheel 42.

61 is a stop lug also projecting forwardly from the face of the wheel 42 and in a position to engage the edge of the sector 45 under certain conditions of operation. If desired the wall 50 of the opening 52 in the flange 44 may be continued as a cam surface 62 leading gradually from the normal thickness of the flange to the substantially thicker end portion thereof at 50.

The frame 41 is provided with an offset portion 63 lying substantially in the plane of the disk member 38. The frame has an opening 64 whose outer wall consists of a series of inclined faces 65, separated by curved sockets 65^a. Within such curved sockets, in the normal operation of the machine, lie rolls 66 having flanges 67, 68 overlying the opposite surfaces of the member 63, whereby the rolls are maintained in operative position. These rolls as clearly indicated in Fig. 3, bear upon the outer surface 39 of the disk 38, and when the shaft 5 is turning in its normal counterclockwise direction, such rolls rotate freely in their sockets.

If, however for any reason the shaft should start to rotate in the opposite direction, the rolls will be carried against the inclined faces 65, and are thereby made to serve as roller brake elements, securely holding the shaft against rotation in such reverse direction.

The member 63, as herein disclosed, is provided with an outstanding arm 69 provided with an elongated substantially radial slot 69^a, such slot receiving loosely therein a pin 70 fixed to the machine frame.

The frame 41 has been shown in Fig. 1 as occupying the position which it will normally occupy when the shaft 5 is turning. In Figs 2 and 3 a modified arrangement of the frame 41 has been shown the mode of operation however being unchanged.

In the operation of the device above described, and with the parts normally positioned as indicated in Figs. 1 and 2 the shaft 5 may be driven by engagement of the lug 31 with the lug 48 of the dog 47. The latter through its connection to sector 45 serves to turn the shaft. The wheel 42 will normally rotate with the shaft due to the reaction of the spring 58 against the lug 60 and also by reason of the engagement of the actuator 49 with the walls 50, 51 of the flange 44. As the fiber is doffed from the spike apron, the scale pan 7 becomes loaded until it tips, thereby swinging the scale-beam 8. This lifts the rod 9, tilting the trip 10 and permitting the dog 12 to engage its tooth 11 with a lug 14 of the wheel 42. Immediately upon stopping the rotation of wheel 42, the continued rotation of the sector 45 under the

momentum of the driven parts serves to out-draw the actuator 49 from the opening 52. The wall 50 serves during such action as a cam to swing the actuator inwardly about 5 its pivot 58.

In the normal operative position of the parts, the reaction of spring 58 is such as to force the nose 49^a of the actuator into contact with the cam wall 51 of slot 52. The 10 engagement of these parts serves to overcome any tendency of the spring to swing dog 47 about its pivot 46. As however, the actuator is positively swung inwardly by the cam wall 50, the pin 56 comes into contact with the right hand wall of slot 55, thus 15 swinging the dog 47 about its pivot 46 until the lug 48 is disengaged from the drive lug 31. When the outer end of the lug 48 has moved out of engagement with the lug 31, 20 the leverage of the spring 58 upon the tail 57 of the dog serves immediately to swing the dog 47 still further. When the pin 56 engages the inner end of the slot 54 the dog continues to move under action of the spring 25 until pin 56 engages the left hand wall of slot 55. The lugs 31 of the drive pulley may now rotate freely past the lug 48 of the dog without striking the same or causing undesirable noise.

30 The shaft 5 comes to rest while the pulley 6 continues to rotate, and the parts remain in the position last described until, upon dumping of the scale pan through the action of the connections previously described, 35 the dog 12 is restored to normal position wherein it is disengaged from the teeth 14 of the wheel 42. Immediately upon such disengagement, the spring 58, reacting against the lug 60, turns the wheel 42 in a 40 counter clockwise direction, causing the relatively stationary actuator nose 49^a to contact with the cam surface 51. The actuator is thereby caused to protrude through the opening 52, and by engagement of the 45 pin 56 with the left-hand wall of the slot, the dog 47 is caused to swing outwardly, whereby to bring its lug 48 into the path of one of the pulley lugs 31, thus again serving to rotate the shaft 5.

50 As the shaft 5 is brought to rest, there is a tendency for the spike apron, which is loaded on its upgoing side with fiber, to reversely rotate such shaft 5, and this is accentuated by the action of the vibrating 55 comb. To prevent such reverse rotation, the roller brake device comprising the frame 41 and the rollers 66 has been provided. The rollers 66 by engagement with the disk 38, serve to hold the shaft 5 securely against 60 any reverse rotation.

As the parts driven by the shaft 5 have considerable weight and momentum, it has been found to occur, when a clutch such as that disclosed in the patent to Howe above 65 noted is employed, that after the clutch dis-

engaging wheel has been stopped, the momentum of the shaft may carry the sector member to a point such that the driving dog may strike forcibly against the hub of the sector. In the present device however, the 70 parts have been so proportioned that such striking and locking of the parts under the momentum of the shaft has been substantially eliminated. The sector, with the dog 47, and the actuator 49, may swing freely 75 within the flange 44 as clearly indicated in Fig. 4. As it is found in practice however, that such movement seldom extends more than a quarter revolution, it has been found desirable to place a stop lug 61 at a point 80 such as to permit any desired turning of the sector with reference to the locked wheel 42, while still serving to limit unnecessary manual movement of these parts, whereby breaking stress might be imposed on 85 spring 58.

In a device such as that shown in the patent to Howe above noted, it is sometimes found that if in stopping, the drive dog is carried into positive engagement with the 90 hub of its supporting sector, as above described, the stop dog can not be disengaged from the tooth of the clutch disengaging wheel. This locking appears to be due to the fact that the locking pawl therein employed 95 is able, due to the twisting of the shaft under momentum, to secure a hold upon the ratchet wheel so advanced that it serves to retain the torsional strain in the shaft. This puts an extremely heavy strain upon the 100 dog which engages the tooth of the clutch disengaging wheel, and such strain may be so great as to prevent the ready disengagement of such dog. In accordance with the present invention however, the freedom of 105 movement of the sector 45 serves to avoid any such locking of the parts, as the sector is free to turn under the effects of momentum, and may move backward to the slight extent necessary to reduce the torsional 110 strain in the shaft to zero.

The roller brake reverse preventing device as herein constructed is also of utility in preventing such locking of the parts and would be effective for this purpose even if 115 applied to a clutch such as disclosed in the patent to Howe, referred to. To permit the roller brake device to have this function, its frame 41 has been furnished with the slot 69^a above referred to. In the normal position, during driving of the shaft, the friction between the rolls 66 and the disk 38 serves to retain the frame 63 in such position that the pin 70 contacts with the bottom wall of slot 69^a (or the right-hand wall 120 thereof as shown in Fig. 2). Upon stopping of the shaft 5 and disengagement of the clutch elements, the torsional strain in the shaft will be reduced to zero by the slight 125 backward movement of the frame 41 permit- 130

ted by the play of pin 70 in slot 69^a. Such movement need be of but small amount to accomplish the desired result. Immediately upon the reduction of the torsional strain, the rolls 66 become effective to hold the shaft against reverse rotation.

While the invention has been herein disclosed as employed in a machine of the specified type, it is clearly evident that the clutch device herein disclosed may be of general application and it is further clear that various changes and modifications in the shapes and arrangements of parts might readily be introduced without in any manner departing from the spirit of the present invention.

Having thus described the invention in a preferred embodiment of the same together with the mode of use thereof what I claim and desire to secure by Letters Patent of the United States is:—

1. A driven shaft and a driving pulley and in combination therewith, a clutch device for connecting the pulley and shaft, said clutch device comprising a support fast on the shaft, a driving dog pivoted on said support, said dog having a tail projecting beyond its pivot, a spring element engaging the tail of the dog and constantly tending to swing said dog to inoperative position, and means constructed and arranged to render such spring element ineffective to swing the dog during the normal, driving operation of the clutch, but in stopping to permit such spring to become effective for such purpose upon movement of the dog initiated by other means.

2. In combination with a shaft, a clutch whereby the same may intermittently be driven, said clutch comprising a support fast on the shaft, a driving dog pivoted upon said support, said dog having a driving nose at one end and a tail at the opposite end, a rotatable part engageable with said nose for driving said dog, and a spring element engaging the tail of the dog and constantly tending to swing said dog whereby to disengage the driving nose thereof from said rotatable part, and means normally operative when the clutch parts are in driving position to oppose the swinging of the dog about its pivot by said spring.

3. In combination with a driving pulley and a driven shaft, a clutch device interposed therebetween and having disengageable elements together with mechanism for disengaging said elements, said clutch comprising a driving lug fast to said pulley and moving in a fixed circular path, a support fast to said shaft, a driven member pivotally mounted on said support and shiftable into and out of said fixed path, and a coiled spring member surrounding said shaft and having one extremity thereof engaging said shiftable member, said spring being opera-

tive alternately to move said shiftable member toward and from said path.

4. In combination with a shaft, a pulley loose thereon, and a clutch interposed between said pulley and shaft, said clutch comprising a driving lug fast to said pulley and moving in a fixed path about said shaft, a support fast to the shaft, a dog pivoted upon said support and having an element engageable by said driving lug, a clutch shifting wheel loose on the shaft, said wheel having a circumferential flange, and an actuator having an arm normally projecting through an opening in said flange, the parts being constructed and arranged to permit the complete withdrawal of said arm from said opening upon disengagement of said driving lug from the dog.

5. A clutch having disengageable elements and comprising a driving member and a driven member, one member moving in a fixed circular path and the other member being shiftable into and out of said fixed path, and a single spring device having an element thereof in direct engagement with said shiftable member whereby to move said member completely away from said path in stopping, and means engaging another element of said spring device and indirectly operative thereby to restore said shiftable member to operative position in starting.

6. A clutch having disengageable elements and mechanism to engage and disengage said elements, said clutch comprising a driving member and a driven member, one member moving in a fixed circular path and the other member being shiftable into and out of said fixed path, and a spring having one extremity in engagement with said shiftable member, said spring being constructed and arranged upon disengagement of said elements directly to move said shiftable element away from said fixed circular path and to become operative thereafter indirectly to restore said member to such path for reengaging said elements.

7. In combination with a shaft and a driving pulley, a clutch comprising a driving lug fast to said pulley, a support fast to the shaft, a driving dog mounted upon the support, a clutch shifting wheel loose upon said shaft, a lever member pivoted to said dog and having an arm normally in operative engagement with an element of said shifting wheel, the parts being constructed and arranged to permit disengagement of said arm and element upon stopping said wheel.

8. In a clutch device, a drive pulley having a lug thereon, a shaft having a dog for engagement by said lug, a rotatable stopping wheel, means carried by said shaft and normally operative positively to rotate said stopping wheel and means for bringing said stopping wheel to rest, the parts being constructed and arranged automatically to com-

pletely disengage said stopping wheel driving means therefrom as said wheel is brought to rest.

9. In a clutch device a shaft, a drive pulley loose thereon, a lug carried by said pulley, a support fast on the shaft, a dog pivoted to said support and having an arm engageable with said lug, a lever pivotally secured to said dog and having an outstanding arm, a stopping wheel loose on the shaft and having a flange provided with an opening through which said arm normally projects, and means for bringing said stopping wheel to rest, the parts being so constructed
10. and arranged as to permit said lever arm to be withdrawn completely within said flange and to move therein in an arcuate path of substantial extent upon cessation of movement of said stopping wheel.
11. 10. In a clutch device in combination a shaft, a drive element movable in a circular fixed path about said shaft as an axis, a support fast to the shaft, a dog pivoted to said support and having a part for engagement with said drive element and being also provided with a substantially radial slot, an actuator comprising a bell crank lever pivoted to said dog and having a pin projecting from one of its arms and loosely engaging

said slot, a stop wheel loosely mounted upon the shaft and provided with a flange having an opening through which loosely projects the other arm of said bell crank lever, a spring encircling said shaft and having one end engaging said dog and its opposite end secured to said stop wheel, and means for bringing said stop wheel to rest.

11. In a clutch device, in combination a shaft, a pulley loosely rotatable thereon, a support fast to the shaft, a drive dog pivoted to said support and engageable by an element of said pulley, a stop wheel freely rotatable on said shaft and having a circumferential flange, a part engageable by an element of said flange for shifting said dog out of engagement with the driving element of the pulley, a stop lug projecting from said stop wheel and means for bringing said stop wheel to rest, the parts being so constructed and arranged that upon cessation of movement of said stop wheel, said shaft with the fixed support may continue its movement under momentum until said support is arrested by said stop lug.

Signed by me at Boston, Massachusetts, this third day of December, 1920.

JOSEPH B. HOWE.
